UNITED STATES PATENT OFFICE.

ALLEN BURCH, OF FULTON, MISSISSIPPI.

CHURN.

950,592.

Specification of Letters Patent.

Patented Mar. 1, 1910.

Application filed November 4, 1909. Serial No. 526,236.

To all whom it may concern:

Be it known that I, ALLEN BURCH, a citizen of the United States, residing at Fulton, in the county of Itawamba and State of 5 Mississippi, have invented a new and useful Churn, of which the following is a specification.

The objects of the invention are, generally, the provision in a merchantable form, 10 of a device of the above mentioned class, which shall be inexpensive to manufacture, facile in operation, and devoid of complicated parts; specifically, the provision of a supporting frame of novel and improved 15 construction; of a shaft for the rotation of the dasher of the churn; of lever mechanism operatively connected in a novel manner with the shaft; of novel means for limiting the movement of the lever; and of a dasher 20 of novel and improved construction; other and further objects being made manifest hereinafter as the description of the invention progresses.

The drawings show but one form of the 25 invention, and it is to be understood that changes, properly falling within the scope of what is claimed, may be made, without departing from the spirit of the invention.

Similar numerals of reference are employed to denote corresponding parts throughout the several figures of the drawing, wherein;—

Figure 1 is a perspective; Fig. 2 is a sectional detail, parts being in elevation; and 35 Fig. 3 is a fragmental top plan of the operating lever, parts being shown in section.

The fundamental member of the device is a frame, which may be of any form. In the present instance, the frame comprises 40 diverging legs 1, connected by side bars 2, the adjacent faces of which are parallel to each other, the side bars being connected by cross pieces 3, from which rise corner standards 4, connected by caps 5, braces 6, uniting 45 50 with the caps 5 and with the standards 4 to complete the upper extremity of the frame.

Secured to one of the cross pieces 3 and to one of the caps 5 is an upright fulcrum post 7, to which the lever for operating the 55 device is pivoted. As shown most clearly in Fig. 3 of the drawings, this lever comprises an arm 25 provided at one end with bifurcations 9 whereby the lever is pivotally assembled with the fulcrum post 7. Inter-

mediate its ends, the arm 25 is bent to form 55 a lateral extension 26, and between the extension 26 and the bifurcations 9, the arm 25 carries an outstanding lug 28. The end of the arm 25 is adapted to be inserted into a handle 8, the handle 8 abutting against 60 one end of the extension 26. Mounted in the end of the handle 8 is a pin 21, prolonged through the lateral extension 26 of the arm 25, the lug 28 being adapted to receive the end of the pin 21, so that the pin may not 65 accidentally be displaced. The arm 25 is secured to the handle 8 by means of a transverse retaining element 29, a screw or the like. The extension 26 of the arm 25 is adapted to receive a shaft 10 provided with 70 spirally disposed slots 11, the pin 21 being adapted to extend through the slots 11. A wear plate 22 is mounted upon the lower face of one of the caps 5 and through this wear plate 22 extends a pin 12, which is 75 mounted in the upper extremity of the shaft 10.

Mounted upon one of the cross pieces 3, is a thrust-plate 15, through which passes a rod 14, carrying at its lower end, the dasher. 80 The upper end of the rod 14 extends into the lower end of the shaft 10 and is secured therein by means of a set screw 16 which is radially inserted into the shaft 10 adjacent the lower end thereof. The thrust-plate 15 85 extends beyond the cross piece 3 upon which it is mounted, and is bent upwardly and curved inwardly, as denoted by the numeral 17, toward the shaft 10. This portion 17 of the thrust-plate is rendered resilient, and is 90 adapted to receive the handle 8 as the lever of which the handle 8 is a component part, moves downwardly. The resilient head 17 of the thrust-plate is adapted to receive 95 yieldingly, the lever, as the machine is operated, and to prevent the lever from working with a jar or shock, as the handle-end 8 of the lever is reciprocated. Moreover, the portion 17 of the thrust-plate serves to space the handle 8 against contact with the set 100 screw 16, it being noted that as the portion 17 of the thrust-plate is compressed by the handle 8, it is impossible for said portion 17 to strike the set screw 16 as the latter rotates with the shaft 10.

The dasher which is assembled with the lower end of the rod 14 is fashioned from a single piece of metal, cruciform in outline,

opposite arms 18 thereof being upwardly bent, and opposite arms 19 thereof being downwardly bent, the lateral edges of all of the arms being outwardly flexed, as denoted by the numeral 20.

The construction last above described results in a dasher simple in construction, and easily manufactured, yet efficient in operation.

10 The operation of the device will probably be evident from the foregoing description, but it may be stated briefly, at this point, that when the handle 8 of the lever is reciprocated vertically, the pin 21 moving in the 15 slots 11 of the shaft 10, will cause a rotation of the shaft, the shaft carrying with it, in its rotation, the rod 14, and the rod 14 causing a rotating of the dasher within the cream receptacle, the upturned end 17 of the 20 thrust-plate receiving, yieldingly, the handle 8 upon its down stroke, and preventing the handle as it is reciprocated, from coming into contact with the set screw 16, as the latter rotates with the shaft 10.

25 Having thus described the invention, what is claimed is:—

1. A device of the class described comprising a frame; an arm pivoted at one end to the frame, and bent, intermediate its ends, 30 to form a lateral extension; a handle arranged to engage the other end of the arm; a pin mounted in the arm and prolonged through the extension, there being a lug upon the arm to receive the other end of the 35 pin; a dasher; and means engageable by the pin to operate the dasher.

2. A device of the class described comprising a frame; an arm pivoted at one end to the frame, and bent, intermediate its ends, 40 to form a lateral extension; a handle arranged to engage the other end of the arm and to abut terminally against the extension; a pin mounted in one end of the arm and prolonged through the extension, there 45 being a lug upon the arm to receive the other

end of the pin; a dasher; and means engageable by the pin to rotate the dasher.

3. A device of the class described comprising a frame; a thrust-plate mounted thereon; a shaft resting upon the thrust-plate and rotatable thereon; a dasher operable by the shaft; a lever fulcrumed in the frame and operatively connected with the shaft; the extremity of the thrust-plate being 50 arranged to receive the lever.

4. A device of the class described comprising a frame; a thrust-plate mounted thereon; a shaft resting upon the thrust-plate and rotatable thereon; a dasher operable by the shaft; a lever fulcrumed in the 60 frame and operatively connected with the shaft; the thrust-plate having a resilient, upwardly curved end to receive the lever.

5. A device of the class described comprising a frame; a thrust-plate mounted 65 thereon; a rod rotatably mounted in the thrust-plate; a dasher carried by the rod; a shaft resting upon the thrust-plate and inclosing one end of rod; means projecting from the shaft for connecting the shaft with 70 the rod; and a lever fulcrumed in the frame and operatively connected with the shaft; the thrust-plate having a resilient upwardly curved end to receive the lever, to space the 75 same against contact with the connecting means.

6. A churn-dasher fashioned from a cruciform piece of material, having opposite of its arms upwardly inclined, and opposite of its arms downwardly inclined, the lateral 80 edges of all of said arms being outwardly bent.

In testimony that I claim the foregoing as my own, I have hereto affixed my signature in the presence of two witnesses.

ALLEN BURCH.
